SCREEN-DOOR CHECK.

1,117,230.

Specification of Letters Patent. Patented Nov. 17, 1914.

Application filed July 21, 1914. Serial No. 852,274.

To all whom it may concern:

Be it known that I, ALBERT A. PAGE, a citizen of the United States, residing in the town of East Haven, county of New Haven, 5 and State of Connecticut, have invented certain new and useful Improvements in Screen-Door Checks, of which the following is a full, clear, and exact description.

This invention relates to door checks, and 10 more particularly to checks for screen doors, and other light doors.

The primary object of the invention is to provide a simple, reliable and inexpensive door check of the pendant type, wherein a 15 suspended buffer on the door is thrown by centrifugal force as the door closes into contact with the jamb, after which, as the door rebounds, the buffer swings inward to clear the door jamb, and permit the door to close 20 with decreased force. More particularly, it is aimed to provide a door check having improved means for mounting and limiting the movement of the buffer hanger, which means is so formed and arranged as to permit 25 the free swinging movement of the buffer hanger. The buffer hanger may be in the form of a straight rod, which has no binding contact with the door, or other part.

To these and other ends, the invention 30 consists in the novel features and combinations of parts to be hereinafter described and claimed.

In the accompanying drawing, Figure 1 is a fragmentary perspective view of a door 35 equipped with a door check embodying my improvements; Fig. 2 is a side elevation of the door check; Fig. 3 is a rear view of the check, showing it detached from the door; and Fig. 4 is a section on line 4—4 of Fig. 3.

40 Referring to the drawings, the improved door check is shown as comprising a hanger 10, secured to the door 11, by means of an inclosing member or cap 12, and screw 13, and carrying at its lower end a buffer 14. 45 The hanger 10 preferably consists of a straight metal rod, or heavy wire, having an eye 15, at the upper end thereof, supported on the screw 13 within the cap 12. The screw 13 not only secures the cap to the 50 door, but also serves as a pivotal support for the hanger. The side wall of the cap 12 is of such width or depth that when the hanger is engaged with the screw 13 in the outermost part of the cap, the buffer will

swing clear of the face of the door without 55 the necessity of bending the hanger.

In order to hold the hanger 10 permanently in the proper position relative to the cap, the clearance opening 12^a in the lower portion of the cap, through which the 60 hanger extends, is formed only in the outermost portion of the cap, there being a shoulder 16 arranged at the inner side of said opening to prevent the eye 15 from working inward in the cap. In this manner, the 65 hanger is effectively prevented from binding when the device is in use. The shoulder 16 forms a stop for the hanger, which prevents the buffer from contacting with the face of the door when the hanger is disposed 70 vertically. In any case, the arrangement is such that even if the buffer does contact with the door, the device is prevented from binding, because the upper end of the hanger cannot be moved inward substantially 75 beyond a plane passing through the center of the buffer, and parallel to the face of the door.

The clearance opening 12^a in the outermost part of the cap rim permits the hanger 80 to oscillate about the axis of the screw 13, but at the same time limits its oscillatory movement in both directions. The hanger is normally suspended vertically, and the clearance opening permits a slight swinging 85 movement on both sides of a vertical plane, passing through the point of suspension and perpendicular to the face of the door.

In order to fix the cap 12 against angular 90 dislocation, the rim thereof may be provided with spurs 12^b adapted to penetrate the wood of the door.

When the door is forcibly closed, the hanger and the buffer will be swung outward by centrifugal force so that the buffer will strike the door jamb 17, as indicated by the dotted lines in Fig. 1. As the door rebounds, and is slowed down, the hanger gradually moves back to its vertical position wherein the buffer clears the door jamb and permits the door to close. The swing of the hanger is effectively limited by the slot in the rim of the fastener cap, and said cap suspends and guides the upper end 100 of the hanger for easy movement about the pivot. By having the fastener cap deeper 105 than the radius of the buffer 14, as shown,

and confining the straight buffer hanger in a shallow slot or opening in the outermost part of the cap, there is no binding against the door at any point, and therefore a straight hanger may be employed with very good results. The device may be very readily applied to the door by forcing the spurs 12^b into the wood at the proper point with the clearance slot lowermost and the shank 10 suspended from the cap, after which the screw 13 is screwed through the outer wall of the cap and through the hanger eye to fasten the parts securely to the door.

The cap and hanger are permanently fastened together independently of the attaching screw in such a manner that said parts, although freely movable relative to each other, cannot, at any time, become entirely separated. This is a great convenience in packaging and selling the check, and also in applying the same to the door. In the form shown, this end is attained by making the eye 15 larger than the clearance slot 12^a so that the hanger may be suspended from within the cap without falling out of the latter. Moreover, in the form shown, the cap is provided with shoulders 18, which, when the hanger is so suspended, engage the under part of the eye, and hold the eye in approximate alinement with the screw opening in the cap, so that the fastening screw may be readily entered through the hanger eye. The device is assembled by inserting the end 19 of the hanger through the clearance slot, from the inside of the cap, then placing the buffer on the lower end portion of the hanger and upsetting the end 19 of the hanger to retain the buffer permanently on the latter, a washer 20 being interposed between the buffer and the enlarged lower end of the hanger, if desired.

The buffer is shown as comprising a disk, freely rotatable on the hanger, but I may use a ball shaped buffer, or one of any other appropriate shape.

Without limiting myself to the construction shown, I claim:—

1. A screen door check, comprising a buffer, a straight hanger therefor, a deep fastener cap for the hanger, and means for suspending the hanger from the cap at a distance from the door at least substantially equal to the radius of the buffer; substantially as described.

2. A screen door check, comprising a buffer, a hanger therefor, a deep fastener cap, means for securing the fastener cap and hanger to the door, with the hanger extending into the cap, and means for retaining the hanger in the outermost portion of the cap; substantially as described.

3. A screen door check, comprising a buffer, a hanger therefor, a deep fastener

cap having a slot in its outermost portion only, through which the hanger is inserted, and means for securing the cap and hanger to the door; substantially as described.

4. A screen door check, comprising a buffer, a hanger therefor, a fastener cap of greater depth than the radius of said buffer, said cap having a clearance opening at its lower part, for the insertion of the hanger, and a shoulder to retain said hanger in the outermost portion of the cap; substantially as described.

5. A screen door check, comprising a buffer, a straight hanger therefor having an eye, a cap fitting over said eye, and a fastening member for the cap engaging said eye within the cap, and directly supporting the hanger; substantially as described.

6. A screen door check, comprising a fastening member, a straight buffer hanger having an eye engaging, and supported on, said fastening member, and a movement-limiting cap for said hanger secured to the door by said screw; substantially as described.

7. The combination with a door, of a relatively deep cap applied to the face of the door, and having an opening at its lower part, and a buffer device having a shank extending upward into the cap, through said opening, and suspended from the door beneath said cap, said opening being formed and located to permit a swinging movement of the buffer device in a lateral direction, but to prevent the upper end of the hanger from contacting with the door; substantially as described.

8. The combination with a door, of a cap applied to one face of the door, and cut-away at its lower portion, a hanger extending upward through said cut-away portion of the cap and pivoted to the door beneath said cap, and a shoulder at the inner side of said cut-away portion to prevent binding of the hanger; substantially as described.

9. A screen door check, comprising a buffer hanger and a cap permanently secured to each other when the check is detached from the door; substantially as described.

10. A screen door check, comprising a buffer, a hanger therefor, and an attaching cap for the hanger slidable relative to the hanger, but permanently secured thereon when the check is detached from the door; substantially as described.

11. A screen door check, comprising a buffer hanger, an attaching member therefor, and a movement-limiting cap for said hanger permanently secured to the latter, independently of said member; substantially as described.

12. A screen door check, comprising a hanger, a cap having a slot engaging said

hanger, an eye on said hanger to prevent removal of the cap from one end of the hanger, and a buffer on the hanger to prevent removal of the cap from the other 5 end of the hanger; substantially as described.

13. A screen door check, comprising a buffer hanger having an eye, an inclosing cap for said eye having a slot through one 10 wall, through which slot the hanger projects, said eye being larger than said slot to prevent the hanger from falling out of the cap; substantially as described.

14. A screen door check, comprising a 15 buffer hanger having an eye, an inclosing cap for said eye having a continuous-sided

opening through one wall, through which opening the hanger projects, said eye being larger than said opening to prevent the hanger from falling out of the cap, said cap 20 having an opening for an attaching member, and means on the cap to suspend the hanger arm with the eye in approximate alinement with said last named opening; substantially as described. 25

In witness whereof, I have hereunto set my hand on the 18th day of July, 1914.
